UNITED STATES PATENT OFFICE.

GEORGE SCALLY, OF CHICAGO, ILLINOIS.

SAFETY DEVICE FOR LOCKS.

Application filed November 18, 1926. Serial No. 149,012.

The lock that is operated with a common key can easily be opened by unauthorized persons. If the lock be on the door of a room and the key be left in the lock on the inner side of the door, the key may either be pushed out of the lock, or it may be gripped in suitable pliers and turned from the outside; so that the presence of the key in the lock is not a safeguard against unauthorized unlocking from the opposite side of the door or the like.

The object of the present invention is to produce a simple and compact device, that may be made at a low cost, for effectively insuring against the unauthorized unlocking of a lock of a certain type, when my improved device is applied thereto.

In carrying out my invention I employ a main member somewhat similar to a door key but having the wing part shorter in the dimension at right angles to the shank of the member than is the corresponding dimension of the key for opening the lock. The shank is so constructed that it may be moved lengthwise into the lock through the large end of the key hole and, when it has been moved in the proper distance, may drop down into the narrow portion of the key hole slot and be interlocked with the walls of the lock casing against endwise movement. After the safety member has been inserted in the lock, a guard device is inserted above the same in the large end of the key hole, to prevent the lifting of the safety device. This guard member is associated with the safety device in such a manner that it may freely be moved between a working position and an idle position and, when in its working position will be positively held against being pushed or driven out of the key hole from the opposite side of the lock.

The various features of novelty whereby my invention is characterized will herein after be pointed out with particularity in the claims; but, for a full understanding of my invention and of its objects and advantages, reference may be had to the following detailed description taken in connection with the accompanying drawing, wherein:

Figure 1 is a vertical section through a door having a set-in lock, my improved safety device being shown as applied to the lock, the catch or guard being in its idle or release position; Fig. 2 is a view similar to Fig. 1, showing the safety device locked in place; Fig. 3 is a section taken approxi-

mately on line 3—3 of Fig. 1; Fig. 4 is a view of a fragment of the lock casing or escutcheon plate, containing the key hole, showing the main member of the safety device entering the key hole and Fig. 5 is a view similar to Fig. 4, showing the main member of the safety device dropped down in the key hole; Fig. 6 is an enlarged detail of the outer end of the safety device; and Fig. 7 is a section taken approximately on line 7—7 of Fig. 6.

Referring to the drawing, 1 represents a lock casing having parallel side walls 2 and 3 containing registering key hole slots 4. My improved safety device comprises a main body member and a locking bolt. The main member consists of a shank 5 similar to the stem of the key for the lock; there being a long narrow wing 6 on one side of the stem at one end. This wing is not as deep, that is as wide as the bolt-operating wing on the key, but it is preferably made as long as or longer than the thickness of the lock as a whole. The shank is notched, as indicated at 7 and 8 at points spaced apart a distance equal to that between the walls 2 and 3 of the lock casing; the purpose of these notches being to reduce the thickness of the stem at two points, so that when these points are brought into registration with the two side walls of the lock casing, the shank or stem can drop down into the narrow portions of the key holes and become interlocked with the lock casing against endwise movement. The wing 6 of course, prevents the safety device from being rotated.

Cooperating with the main member of the safety device is a bolt 9 that is adapted to be slipped into the large ends of the key holes and prevent the other member from being lifted up. The bolt may be permanently attached to the shank or stem 5 by a suitable clip 10 bent around both of these members and permitting relative rotary and endwise movements between them. Some means must be provided to prevent unauthorized rotation or endwise movement of the bolt 9. In the arrangement shown, the stem or shank 5 has at one end a head 11 in the form of an eye or ring open directly opposite the end of the stem or shank. The locking bolt has a head flattened in one direction and elongated in the direction at right angles thereto; the parts being so proportioned that when the head on the locking bolt is turned so as to bring its long dimen-

sion into the plane of the stem and the bolt, a portion of the head enters the opening in the ring or head 11 and locks the bolt against endwise movements. Such a condition is shown in Figs. 2 and 6. When the safety device is to be applied to or removed from the lock, the bolt is turned about its long axis through an angle of ninety degrees from the position shown in Figs. 2 and 6, namely into the angular position shown in Fig. 1, whereby the bolt becomes free to be moved endwise.

The entry of the head on the locking bolt into the notch in the head or ring on the safety element prevents endwise movements of the locking bolt, but does not prevent rotary movements. The bolt can be locked against rotary movements in any suitable way, conveniently by loosely securing in the eye 11 an eyelet 13 whose flanges extend radially far enough to overlap the ends of the head 12 on the locking bolt when the latter is in its locking position. At least one of the flanges of the eyelet is cut away to form a notch 14 through which, when it is brought in registration with the notch or opening through the side of the eye 11, the head of the locking bolt may freely swing.

It will be seen that my invention consists of a small device that may be carried about on one's keyring in the same way as a key and, at night or at other times, in a hotel room or elsewhere, the device may quickly be applied to the key hole of the door and positively insure against unlocking of the door from the outside.

While I have illustrated and described with particularity only a single preferred form of my invention, I do not desire to be limited to the exact structural details thus illustrated and described; but intend to cover all forms and arrangements which come within the definitions of my invention constituting the appended claims.

45 I claim:

1. A device of the character described comprising a stem having a long narrow radial wing at one end, said stem being grooved at two points distributed along said wing a distance equal to the thickness of a lock casing, to permit the stem to drop down into the narrow portions of the key hole slots in the casing after being inserted in the large ends of the slots, and a guard member adapted to overlie the stem within the large ends of the key holes, and means for detachably locking said guard member and stem together.

2. In combination, a stem having at one end a long narrow wing, the stem being grooved opposite the said wing along lines separated a distance equal to the thickness of a lock casing; a locking bolt lying upon the stem on the side opposite the wing, means securing the bolt and the stem together to permit relative longitudinal movements, and means for locking the bolt to the stem to prevent relative longitudinal movements.

3. In combination, a stem having at one end an eye open at the juncture with the stem, an eyelet in said eye having in one side a notch adapted to register with the gap in the eye, a bolt lying beside said stem and having a head adapted to extend into said gap in one angular position of the bolt and to clear the gap in another angular position, a clip securing said stem and said bolt together, a long narrow wing on one side of the stem at the opposite end, and there being transverse notches cut into said stem opposite the said wing at a distance apart equal to the thickness of a lock casing.

4. A device comprising two members adapted to be inserted, one above the other, into a keyhole to fill the same, one of the members having parts interlocking with the element in which the keyhole is located to prevent withdrawal of that member, the second member being mounted on the first member so as to be slidable lengthwise thereof and rotatable about its long axis thereon, the second member having at its outer end a head, and a locking dog on the first member adapted to engage with said head and prevent relative movements between said members.

5. A device comprising two members adapted to be inserted, one above the other, into a keyhole to fill the same, one of the members having parts interlocking with the element in which the keyhole is located to prevent withdrawal of that member, the second member being mounted on the first member so as to be slidable lengthwise thereof and rotatable about its long axis thereon, the second member having at its outer end a head, the first member having a recess to receive said head when the second member is rotated while in a working position and prevent relative lengthwise movements between said members, and a dog on the first member in position to lock said head against rotation out of the recess.

In testimony whereof, I sign this specification.

GEORGE SCALLY.
